UNITED STATES PATENT OFFICE

PHILEMON LEVASSEUR, OF THREE RIVERS, QUEBEC, CANADA

DESIGN FOR A STRINGED INSTRUMENT

Application filed July 9, 1932. Serial No. 44,293. Term of patent 7 years.

To all whom it may concern:

Be it known that I, PHILEMON LEVASSEUR, a subject of the King of Great Britain, residing at Three Rivers, in the Province of Quebec and Dominion of Canada, have invented a new, original, and ornamental Design for a Stringed Instrument, of which the following is a specification, reference being had to the accompanying drawing, forming part thereof.

Figure 1 is a bottom plan view of a musical instrument, showing my new design.

Figure 2 is a perspective view in side elevation thereof.

Figure 3 is a view in top plan.

I claim:

The ornamental design for a stringed instrument as shown.

PHILEMON LEVASSEUR.
